UNITED STATES PATENT OFFICE.

CLARENCE M. LEVETT, OF NEW YORK, N. Y.

DESIGN FOR A FAN.

55,389.

Specification for Design.

Patented June 1, 1920.

Application filed March 17, 1920. Serial No. 366,706. Term of patent 7 years.

To all whom it may concern:

Be it known that I, CLARENCE M. LEVETT, a citizen of the United States, and a resident of the city of New York, borough of Manhattan, in the county and State of New York, have invented a new, original, and ornamental Design for a Fan, of which the following is a specification, reference being had to the accompanying drawing, forming part thereof.

The figure is a perspective view of a fan showing my new design.

I claim:

The ornamental design for a fan as shown.

CLARENCE M. LEVETT.
